United States Patent Office

Des. 209,623
Patented Dec. 19, 1967

209,623

JUG

Earl L. Schaper and Stanley A. Marcus, Midland, Mich.,
assignors to The Dow Chemical Company, Midland,
Mich., a corporation of Delaware

Filed Jan. 3, 1966, Ser. No. 422

Term of patent 14 years

(Cl. D58—5)

Fig. 2

Fig. 1

FIGURE 1 is a side elevational view of a jug, showing our new design;

FIGURE 2 is a top plan view;

FIGURE 3 is an elevational view looking from the left of FIGURE 1;

FIGURE 4 is an elevational view looking from the right of FIGURE 1; and

FIGURE 5 is a cross-sectional view thereof taken along line 5-5 of FIGURE 2.

The dominant features of our design reside in the portions shown in full lines.

We claim:

The ornamental design for a jug, as shown and described.
